UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIO TELEPHONE SYSTEM.

Original application filed September 26, 1924, Serial No. 740,113. Divided and this application filed February 19, 1926. Serial No. 89,409.

My invention relates to systems of communication, and particularly to telephone and radio systems. The present application is a division of my prior copending application, Serial No. 740,113, filed September 26, 1924, patented March 16, 1926, No. 1,577,107. The present invention has for its main object the provision of centralized maintenance and control through the centralization of the source of power or energizing current for the service units. Another object is to provide means for extending centralized power through a system including subcenters such as private branch exchanges, and central radio receiving stations in apartment houses, hotels and the like. Other objects of the invention will be apparent from the following specification and the drawings accompanying the same.

20 My invention is illustrated in the accompanying drawings, in which:

Fig. 1 is a diagram showing a general system embodying the same.

Fig. 2 is a schematic diagram of a private branch exchange system with radiophone receivers at the subscribers' stations supplied with energizing current from a common source secondary to a centralized source at the main exchange.

30 Fig. 3 is a more detailed circuit diagram of the system of Fig. 2.

Fig. 4 is a fragmentary circuit diagram of a modification of the charging system of Fig. 3.

35 Fig. 5 is a further modification of the charging system of Fig. 3 using a local generator.

Fig. 6 is a further modification of the system of Fig. 3 with local generation at the 40 private branch exchange station taking power supply over the phantom circuit.

Referring to Fig. 1, 1, 2 and 3 represent telephone subscribers' stations connected by wires 4, 5 and 6 to the central telephone exchange 7, constituting the distributing center for the area in which local subscribers 1, 2, 3, etc. are located. Superposed upon this telephone system is a radiophone system comprising a central station 8 and subscribers' stations 1^a, 2^a, 3^a, etc. The central radio station or exchange is provided with switchboards and a complete broadcasting equipment, and the subscribers' stations 1^a, 2^a, 3^a, etc., are provided with receiving in-

struments all standardized for the same 55 wave length, and adapted to respond to the waves radiated from the central station 8. The interrelation between the telephone system and the radiophone system is by means of physical connections indicated at 1^b, 2^b, 60 and 3^b at the subscribers' stations, and multiples or trunk extensions 15 from the telephone exchange switchboards to the radiophone exchange switchboard in station No. 8. Stations 12, 13 and 14 in this figure are 65 typical of indifferently located distant stations which may or may not be a part of this particular system.

Briefly stated, as indicated in Fig. 1, each radio central station or radio department of 70 a telephone exchange, is not only provided with broadcasting equipment for its subscribers, but also with radio receivers adjustable by tuning to wave lengths allotted to such stations as those indicated at 12, 13 75 and 14, as well as primary stations maintained and operated by or under the direction of the telephone organization itself. By means understood in the art, messages received at the radio central stations are relayed on their respective standard wave lengths to the local subscribers.

In Fig. 2, I show an arrangement in which the idea of supplying battery current over wires to the radiophone subscribers is applied to private branch exchange systems, in which certain of the trunks T^s, T^e, T^r, and T^g leading from the main exchange M to the PBX station are phantomed with a charging circuit or circuits for storage batteries such as A⁷ and B⁶ which act as a common source of current supply for the radiophones RP¹, RP², etc. associated respectively with the private branch exchange, subscribers' telephone sets T¹⁰, T¹¹, etc. The batteries A⁷ and B⁶ are the "A" and "B" batteries, respectively, for the subscribers' radiophone sets and are connected to the sets through the three bus wires 191, 192 and 193. These batteries A⁷ and B⁶ are arranged to be charged from the central office batteries A⁸ and B⁶, respectively, over separate phantom circuits, or they may be alternately connected for charging to a single phantom circuit.

A more detailed circuit diagram of the arrangement for charging the private branch exchange batteries each over a sepa-

rate phantom circuit and from a separate central office charging battery, is shown in Fig. 3, where the two circuits are grounded phantom circuits imposed on the two trunks 5 T^s and T^e leading from the main exchange M to the private branch exchange station PBX. As the trunk lines are identical, a description of one, T^s will suffice. This consists of a pair of conductors 190—194 terminating in the main exchange at the outside terminals of the winding 195 of a repeating coil 196, and in the PBX station at the outside terminals of the winding 197 of a repeating coil 198. The winding 199 10 of the repeating coil 196 is connected through a cut-off jack 200 to a drop signal 201 at the main telephone station, while at the PBX station the coil 202 is similarly connected through a cut-off jack 203 to the drop signal 204. To facilitate the passage 15 of voice current through the trunk from jack to jack, the repeating coils are bridged by telephone condensers 205 in the usual manner. At the main exchange the trunk side 20 of 195 of the repeating coil 196 is tapped at the middle and connected through a conductor 206 and switch 207 to the plus terminal of the charging battery A^s , the minus terminal of which battery is grounded at the main 25 exchange. Similarly a conductor 208 connects the middle of the trunk side of the repeating coil at the PBX station through a switch 209 to the plus terminal of the battery A^e , the minus terminal of which battery 30 is grounded at the PBX station. The trunk T^s and its terminal apparatus is the same as the trunk T^e and has phantomed on it a charging circuit for the battery B^s which circuit is connected to the battery at 35 the PBX station by way of the conductor 210 leading through switch 211 and conductor 212 to the plus terminal of the battery B^s the minus terminal of which is grounded as shown. At the main station M the phantom 40 circuit is connected with the charging battery B^s by the conductor 213 which leads from the middle point of the trunk side of the repeating coil through the switch 214 to the plus side of the battery B^s , the minus side of which is grounded. Thus, the batteries A^s and B^s are connected to separate 45 charging batteries A^s and B^s , respectively, at the main station over separate grounded phantom circuits, one on the trunk T^s and one on the trunk T^e . The primary sources A^s and B^s at the main exchange are of sufficient voltage to affect proper charging of their respective secondary batteries A^s and B^s . The common-battery supply busses 191, 50 55 60 65 192 and 193 are the same as those of Fig. 2, and so are multiplied to the battery consuming elements in the radio receivers. For example, where a detector tube or single tube set is used as indicated in Fig. 3, the filament and supply leads 216 and 217 are connected

to the busses 191—192, respectively, while the plate circuit conductor 218 is connected to the bus 193, the plate circuit return being effected through the filament lead 217 to the middle of common bus 192 as is usual where 70 a local set of batteries is used. To keep radio frequency currents off the busses 192 and 193 a radio frequency by-pass condenser 219 is connected as shown.

Where only one charging circuit is available 75 the circuit arrangement of Fig. 4 may be used in which is shown the single phantomed circuit imposed on the trunk T^s arranged to be switched in circuit with the battery A^s and generator A^{10} , or the battery B^s and generator B^s , according to which battery is to be charged. In this arrangement the plate battery B^s is shown tapped at an intermediate point to supply detector voltage to the bus 193, while the 80 fourth bus 220 is led from the extreme positive terminal for supplying plate voltage 85 where amplifier tubes are used.

Fig. 5 shows a further arrangement for supplying current from the main station in 90 which the primary energy is supplied over the trunk line T^{10} in the form of alternating current of superaudio frequency which may or may not be modulated with audio signals but which is transformed into the proper 95 form of energy for charging the secondary batteries A^s and B^s through a suitable high frequency motor 221 and a pair of generators 222 and 223 driven thereby.

In Fig. 6 is shown a further modification 100 of the idea of charging over a phantom circuit in which the batteries are charged by a pair of local generators 224 and 225 driven by a motor 226 supplied with power over the phantom circuit from a source 227 105 at the main station.

The word "radiophone" when used herein means a radio telephone instrument.

What I claim is:

1. In a broadcasting system, a main station, a plurality of subscribers' substations, means for receiving radio waves at each substation, said means including thermionic tubes having filament and plate circuits requiring current at different voltages for 110 their supply, a plurality of local current supply busses common to a group of said substations, part of said busses being appropriated to the filament circuits and part of said busses being appropriated to said 115 plate circuits, and so connected at the several subscribers' stations, trunk wires extending from the main station to a point in proximity to the group of substations served by said busses, means at the main 120 station for supplying current over said trunk wires at different voltages suitable for the plate and the filament circuits respectively, and means connected to said trunk circuit on the one side and the respective 125 130

- pairs of busses on the other side adapted to receive the currents transmitted from the central station and to selectively transmit the same over the appropriate bus circuits 5 to the terminals of the respective filament and plate circuits of the thermionic tubes in the receiving sets at the several subscribers' stations in the associated group served by said busses.
- 10 2. The broadcasting system described in claim 1, in which the means for receiving current over the trunk wires and for selectively directing the same over the bus wires, consist in a plurality of accumulators of 15 suitable capacity and voltage which supply the filament circuits and the plate circuits respectively of the subscribers' instruments.
3. The broadcasting system described in claim 1, in which the trunk wires from the 20 central station and the bus wires extending to the different subscribers in the local group all terminate at a branch exchange, with means whereby an attendant in the branch exchange may supervise and control 25 the reception of radio waves at the subscriber's substation independently of said bus wires.
4. The broadcasting system described in claim 1, in which the trunk wires from the 30 central station and the bus wires extending to the subscriber's local group of substations are both connected to a branch exchange, with means whereby an attendant at said branch exchange may control and supervise 35 the current connection between the trunk wires and the bus wires and the reception of radio waves by the subscribers' receiving sets, respectively.
5. The broadcasting system described in
- claim 1, in which the means for receiving current from the central station over the trunk wires and directing the same selectively over the bus wires, comprise a plurality of storage batteries of suitable voltages and capacity to carry the load of subscribers' stations in parallel, one battery carrying the filament load and another battery carrying the plate load, for energy supply only, whereby charging current may be sent from the central station over the trunk 40 wires for a determinate time and at a determinate rate to accumulate energy in proper quantity to carry the load of the receiving sets at a rate and for a time determined by the receivers, and independent of the conditions of charging.
6. In a broadcasting system, a main telephone exchange station, a plurality of subscribers' substations, means for transmitting radio waves to the substations, means at the 45 substations for receiving said radio waves, a set of current supply busses common to a group of said substations, a telephone trunk circuit extending from the said main station to said busses, a plurality of storage batteries of different voltages for supplying current through said busses to the receiving means at different voltages, means at the 50 main station for supplying current to said trunk at different voltages sufficient to charge said different batteries at different 55 times, and means for connecting the different batteries to the trunk circuit at different times.
- In testimony whereof I hereunto affix my 60 signature.

EDWARD E. CLEMENT.
